(57) **CLAIM**

We claim the ornamental design for an MRI-compatible therapeutic gas injector module, as shown and described.

DESCRIPTION

FIG. 1 is a top, front, and left-side perspective view of an MRI-compatible therapeutic gas injector module showing our new design;

FIG. 2 is a front elevational view thereof;

FIG. 3 is a rear elevational view thereof;

FIG. 4 is a left side elevational view thereof, the right side being a mirror image;

FIG. 5 is a top plan view thereof;

FIG. 6 is a bottom plan view thereof; and,

FIG. 7 is a bottom, rear, and left-side perspective view thereof.

The broken lines in the figures show portions of the injector module which form no part of the claimed design.
